UNITED STATES PATENT OFFICE.

ARTHUR R. JOYCE, OF NEW FAIRFIELD, CONNECTICUT.

HUMIDIFYING APPARATUS.

1,111,837.

Specification of Letters Patent. Patented Sept. 29, 1914.

Application filed July 5, 1913. Serial No. 777,573.

To all whom it may concern:

Be it known that I, ARTHUR R. JOYCE, a citizen of the United States, residing at New Fairfield, county of Fairfield, State of Connecticut, have invented an Improvement in Humidifying Apparatus, of which the following is a specification.

This invention relates to incubators and has for its object to provide novel means for 10 heating the hatching chamber, for ventilating it and for humidifying the air therein. This I accomplish by means of the novel structure which will be hereinafter described, and then specifically pointed out in 15 the claim hereunto appended.

In the accompanying drawings forming a part of this specification, Figure 1 is a vertical longitudinal section of my novel incubator complete; Fig. 2 a detail plan view 20 of the boiler, the circulation pipes and the humidifying pipe detached, and Fig. 3 is a vertical section on an enlarged scale, of the boiler and humidifying chamber, the coöperating pipes being shown partly in section 25 and partly in elevation.

10. denotes the hatching chamber, 11 the boiler, 12 hot water pipes leading from the top of the boiler and passing into the hatching chamber, 13 a single return pipe into 30 which both of the hot water pipes lead and which enters the boiler near the bottom thereof, 14 the humidifying chamber which surrounds the boiler, and 15 a lamp for 35 heating the water in the boiler. It is thus seen that the humidifying chamber 14 comprises inner and outer spaced walls, forming a closed space therebetween. The boiler is provided with a central hot air flue 16 which is of greatest diameter at the bottom and 40 converges toward the top. Rigidly secured in the flue is a draft pipe 17 for the lamp. The upper end of the draft pipe is adapted to be closed by a cover plate 18 loosely suspended from a rod 19 having at its opposite 45 end an adjustable counterweight 21. The lever is fulcrumed, as at 20, in a standard which forms a portion of a thermostat indicated as a whole by 22, the portions of which lying within and without the hatching 50 chamber are connected in the usual manner, so that when the temperature in the hatching chamber rises above a predetermined maximum, the thermostat will cause the lever to tilt and raise plate 18 away from the top of the draft pipe, as shown in Fig. 55 1. The draft will cause the flame of the

lamp to pass through the pipe instead of in contact with the inclined wall of flue 16 in the boiler, thereby causing the temperature of the water in the boiler to be lowered. 60 Should the temperature now fall below the pre-determined minimum, the thermostat will again tilt the lever and cause plate 18 to drop downward and close the draft pipe, the effect of which is to cause the flame of 65 the lamp to pass outside the draft pipe and in contact with the inclined wall of flue 16 in the boiler and thus raise the temperature of the water in the boiler.

The hot water pipes extend in opposite 70 directions after passing into the hatching chamber, then forward and then inward not far from the upper and side walls of the chamber. Both hot water pipes lead into the return pipe which lies midway between 75 the hot water pipes and passes outward through the wall of the chamber and through the humidifying chamber and leads into the boiler near the bottom thereof.

23 denotes an air pipe leading from the 80 hot water pipes at their intersection with the return pipe and outward through the wall of the hatching chamber. This pipe is provided with a cock 24 outside the hatching chamber which is opened when the incubator 85 is placed in operation to permit the air to be driven out from the pipes.

25 denotes an expansion tank from which a pipe 26 extends and connects with the return pipe. A cock 27 at the lower end of 90 pipe 26 permits the water to be drawn off.

28 denotes a circulation pipe in flue 16 which leads from the boiler opposite the entrance of the return pipe, passes in an ascending coil about the draft pipe and 95 again enters the boiler near the top thereof. When the draft pipe is open as in Fig. 1, the water in this pipe will be heated through its contact with the draft pipe and when the draft pipe is closed the water in this pipe 100 will be heated by direct contact therewith of the flame of the lamp with the flue. The object of this pipe is to secure a circulation of water in the boiler by insuring that a portion of the cooler water that enters the boiler 105 from the return pipe will be heated to a higher temperature in the coil than the water in the boiler itself, the current of more highly heated water entering the boiler near the top and causing a constant current of 110 heated water to pass rapidly from the top of the boiler through the hot water pipes.

An important feature of the invention is the means provided for humidifying the air in the hatching chamber, *i. e.* not only restoring to the air its natural moisture but 5 supplying it with any additional degree of moisture that may be desirable to facilitate the process of hatching and wholly prevent the serious loss of chicks which is unavoidable, so far as I am aware, with any incubator that has heretofore been placed in use. 10 This I accomplish by means of the humidifying chamber lying outside of the boiler and heated thereby. Air is supplied to this chamber by means of a supply pipe 29 entering the bottom of the chamber and passes therefrom through humidifying pipe 30 which leads from the top of the chamber into the hatching chamber, opens upward centrally near the top thereof, and 15 is provided with a deflecting plate 31, which causes the air to issue in a sheet. Within the humidifying chamber and secured to the outer wall of the boiler is a spiral vaporizing plate 32, inclined toward 20 the boiler, upon which water drops from a suitable water-dropper indicated as a whole by 33. This water-dropper may be of any ordinary or preferred construction, for example like an ordinary oil feed. In the 25 form illustrated in the drawings a peep-glass 34 is provided in order to show at all times how fast the water is dropping; means, as a knurled nut 35, is provided to regulate the flow and a lever 36 is provided which 30 wholly shuts off the flow. The spiral plate is heated by the boiler and the water that drops thereon is turned into contact with the boiler so that the water is quickly vaporized and effectually moistens the air in the 35 humidifying chamber, which passes by means of the humidifying pipe to the hatching chamber. In practice a hydrometer may be provided to measure the degree of moisture in the hatching chamber, so that a uniform 40 degree of moisture may be maintained at all times by regulating the amount of water that is allowed to drop upon the spiral plate in the humidifying chamber.

The eggs to be hatched are placed upon 45 suitable carriers 37 of less width than the hatching chamber which in order to facilitate the ventilation of the hatching chamber are made of a layer of wire netting, indicated by 38, over which is a layer of burlap 50 or coarse cloth indicated by 39. The chicks after hatching drop over the edge of the egg carriers upon a permeable chick carrier

55 which is preferably made like the egg carriers to consist of a layer of wire netting 38 over which is a layer of burlap 39. In order to insure perfectly uniform conditions, 60 as to temperature and moisture in the portion of the hatching chamber containing the egg carriers I place the hot air pipes, the return pipe and the humidifying pipe in the upper portion of the chamber and below 65 them I place an air screen 41 which may be made of burlap or other coarse cloth, the effect of which is, while not appreciably checking the passage of air, to cause it to 70 be diffused uniformly as regards temperature and moisture throughout the portion of the hatching chamber containing the egg carriers. Perfect ventilation is maintained by causing air to pass out from the hatching chamber through openings 42 in the bottom 75 43. These openings are provided with cover plates 44 raised above them so as to prevent direct draft through the holes. In order to provide that the gases, which are given off when hatching takes place, may be permitted to pass off more quickly than 80 they would through the openings in the bottom I hinge the bottom as at 45 so that it may be dropped down to let the gases pass off quickly, while the chicks are guarded against exposure to the entrance of cold air by the burlap and wire netting of the chick carrier.

Having thus described my invention I 90 claim:

The combination with a humidifying chamber comprising spaced inner and outer walls, providing a closed space therebetween, of a spiral vaporizing plate arranged within the closed space and vertically inclined in cross-section and extending downwardly toward the inner wall to conduct water fed thereon upon the inner wall, means to supply water into the closed space to the upper end of the spiral vaporizing plate, heating means arranged within the inner wall, air inlet means for the closed space, and air outlet means communicating with the closed space and adapted to supply 100 humidified air to a chamber, substantially as described.

In testimony whereof I affix my signature in presence of two witnesses.

ARTHUR R. JOYCE.
